UNITED STATES PATENT OFFICE.

GEORGE C. BUCH, OF EUREKA, MISSOURI.

BOOT OR SHOE.

SPECIFICATION forming part of Letters Patent No. 298,346, dated May 13, 1884.

Application filed March 14, 1884. (No model.)

To all whom it may concern:

Be it known that I, GEORGE C. BUCH, of Eureka, St. Louis county, Missouri, have made a new and useful Improvement in Boots and Shoes, of which the following is a full, clear, and exact description, reference being had to the annexed drawings, making part of this specification, in which—

Figure 1 is a view in perspective of the inner sole; Fig. 2, a view in perspective showing the heel-lining piece attached to the inner sole; Fig. 3, a view in perspective showing the counter and upper attached to the inner sole; Fig. 4, a view in perspective showing the outer sole attached in position; Fig. 5, a view in perspective of the heel; Fig. 6, a view in perspective of the heel-plate, and Fig. 7 a view in perspective showing the heel attached.

20 All of the views are looking toward the under sides of the parts respectively shown.

The same letters of reference denote the same parts.

I have heretofore obtained Letters Patent 25 for an improvement in boots and shoes, on an improved mode of attaching the heel to the boot or shoe.

The present invention is an improvement upon the construction referred to, the improvement consisting in the mode of constructing and combining the inner sole, the counter, and the heel, substantially as herein-after described, and designated in the claim.

30 A, Figs. 1, 2, 3, represents the inner sole. It is provided upon its underside, at the heel, with a welt, A'. The heel-lining piece B, Fig. 2, and the counter C, Figs. 3, 4, are then attached to the inner sole, and as follows: In 35 place of turning the lower edge of the counter

in at the inner sole, and, on the other hand, 40 in place of extending the lower edge of the counter so as, as shown in the patented construction above referred to, to come even with the lower edge of the heel-fastening plate, the lower edge, c, of the counter, as well as the 45 lower edge, b, of the heel-lining piece, is extended and made to come just even with the lower side of the welt A', as shown in Fig. 3. The counter is then attached by means of fastenings c', Fig. 3, passing laterally into the 50 welt and inner sole. The outer sole, D, is then fastened to the inner sole and welt, as in Fig. 4. The heel E is then attached. There is a rabbet, e, extending around the upper part of the heel, and the heel is attached by means of 55 the heel-plate F, Figs. 6, 7, and in the manner shown in Fig. 7—that is, the heel-plate is made to fit into the rabbet e in the heel, and at its upper edge is fastened to the inner sole and 60 welt, and at its lower edge it is fastened to the heel. The fastenings f at the upper edge of 65 the heel-plate pass through the counter into the inner sole, and the fastenings f' at the lower edge of the heel-plate pass directly into the heel. The heel-plate, at its forward ends, is provided with the inwardly-turned extensions f²f², which, as shown in Fig. 7, are secured to the shoe at the front of the heel.

I claim—

The combination, substantially as described, 70 of the inner sole, A, the welt A', the counter C, extended as described, the outer sole, D, the heel E, having the rabbet e and the plate F.

Witness my hand.

GEORGE C. BUCH.
